UNITED STATES PATENT OFFICE.

GEORGE A. GULLBERG, OF HOLDEN, MASSACHUSETTS.

SNOW-REMOVING MACHINE.

Application filed May 29, 1926, Serial No. 112,661. Renewed July 24, 1928.

This invention relates to a machine for removing snow.

Many types of snow removing devices have been designed, but most of them are very complicated in construction and in operation, and they are expensive to manufacture.

This invention has for its salient object to provide a simple and practical device of the character described that can be economically manufactured.

Another object of the invention is to provide a snow removing device that can be easily and quickly attached to a motor vehicle and can be operated from the power shaft of the vehicle.

Further objects of the invention will appear from the following specification, taken in connection with the drawings which form part of this application, and in which

Fig. 1 is a top plan view of a machine constructed in accordance with this invention;

Fig. 2 is a front elevation of the device shown in Fig. 1;

Fig. 3 is an elevational view showing the supplemental supporting means for the frame of the attachment;

Fig. 4 is an elevational view showing the connection between one of the links and one of the slats;

Fig. 5 is a view taken at right angles to Fig. 4;

Fig. 6 is a sectional detail view showing the connection between one of the slats and one of the chain links; and

Fig. 7 is a sectional detail view showing the supporting ledge for the conveyor chains.

The invention briefly described, consists of an attachment adapted to be secured to the front of a motor vehicle, and having operative parts adapted to be driven from the power shaft of the vehicle.

The attachment comprises a frame adapted to extend transversely across the front of the vehicle and a pair of endless chains are mounted on the frame having secured thereto transverse slats. The chains are driven from the power shaft of the vehicle and the slats are moved with the chains across the path of the vehicle and scrape or push the snow laterally to one side of the machine.

Further details of the invention will appear from the following specification.

In the embodiment of the invention illustrated, the device is shown as secured to the front end of a motor vehicle 10. The vehicle has secured thereto a supplemental frame

having longitudinally extending frame members 11 and 12 secured to the front end of the vehicle frame 13. The frame members 11 and 12 have pivotally connected thereto at 14 and 15 longitudinally extending frame members 16 and 17, the rear ends of the members 16 and 17 being disposed beneath stop-lugs 18 and 19. It will thus be seen that the members 15 and 16 can be tilted upwardly about their pivots 14 and 15 but that their downward movement is limited by the stops 18 and 19.

The front ends of the members 16 and 17 have secured thereto a box-shaped frame comprising a bottom 20, a top 21, and ends 22 and 23. The various parts are braced by truss members 24, 25, 26 and 27. The box-shaped frame has vertically extending struts or posts 30 and 31 which are secured to the members 16 and 17 and support the box-shaped frame thereon.

There is also mounted on the frame members 16 and 17 intermediate the box-shaped frame and the vehicle a vertically disposed plate or snow board 32 which is secured, as shown at 33 and 34, to the members 16 and 17. The plate or board 32 carries at its lower end brackets 35, to which are secured caster rollers 36 which aid in supporting the attachment.

The box-shaped frame has rotatably mounted at its ends a pair of shafts 40 and 41, on the front and rear ends of which are secured sprocket wheels 42 and 43. The shaft 41 also has secured thereon a sprocket wheel 44 which is connected by a chain 45 to a sprocket wheel 46 carried by the hub 47 of a cone-clutch member 48 rotatably mounted on a shaft 49. The shaft 49 also has mounted thereon and secured thereto a cone-clutch member 50 adapted to co-act with the clutch member 48. A casing 51 is secured to the plate 32 and encloses the clutch mechanism.

The shaft 49 is connected through a universal joint 53 to the front end 54 of an extension of the power shaft of the vehicle 10. It will be noted that the universal joint 53 is substantially in alignment with the pivots 14 and 15 of the frame members 16 and 17, thus permitting the frame members to be tilted without interfering with the driving connection.

The clutch member 50 has connected thereto a lever 55, which is operated by a rod 56 which will be extended rearwardly in position to be manipulated by the driver of the vehicle.

The snow removing devices are carried by

the chains 38 and 39 consist of a plurality of cross slats 60. Each of the slats has a pair of lugs 61 and 62 extending laterally from each end thereof, and these lugs are mounted on pins 63. The pins 63 form the connections between adjacent links of the chain and are extended endwise as shown in Fig. 6 to receive the lugs 61 and 62. The upper strands of the chains preferably are supported by plates 57 and 58 attached to the top frame 21 (see Fig. 7).

Each of the slats also is connected to two chains by means of struts 65 and 66, these struts also being connected to link pins 63 of the chain and being pivoted to the slats at 67 and 68, these struts 66 exert their pressure on the slats 60.

It will be noted from the showing in Figs. 1 and 2 that each of the slats 60 is extended longitudinally beyond the front chain 39 as shown at 70. The extensions are also made wider than the slats so as to provide a greater snow engaging surface.

The snow removing device operates in the following manner.

Operation.

When the vehicle is advanced and the clutch 48—50 is thrown in, the chains 38 and 39 will be driven, thus moving the slats 60 across the path of the vehicle in the direction of the arrow shown in Fig. 2. The slats will engage and draw the snow across the path of the vehicle, discharging the snow at the right hand side of the path of movement of the vehicle. In this way the snow will be quickly and expeditiously removed, and it will be evident from the construction of the device that it can be easily and quickly attached to and removed from a motor vehicle.

Although one specific embodiment of the invention has been particularly shown and described, it will be evident that the invention is capable of modification, and that modifications and changes in the construction and in the arrangements of the various co-operating parts may be made without departing from the spirit or scope of the invention as expressed in the following claims.

I claim—

1. A snow removing device, comprising frame members extending forwardly in a longitudinal direction from the body of a motor vehicle, a pair of vertical posts secured and supported on said frame member at the front of the vehicle, a box-like frame of which said posts constitute a part thereof supported on said frame members with said frame extending transversely of the vehicle along the front of it, an endless conveyor mounted on said frame and substantially surrounding it and having slats across it for moving the snow from the ground below the frame.

2. A snow removing device, comprising frame members, means for pivotally attaching said frame members to the frame of a motor vehicle, vertical posts secured to and supported on said frame members, a box-like frame carrying said posts and extending transversely of the frame members, sprocket wheels mounted on said transverse frame at the ends thereof, endless chains mounted on said sprocket wheels, means for driving said chains, and cross slats secured to and adapted to travel with said chains, said endless chains surrounding and enclosing said box-like frame.

3. A snow removing device, comprising frame members, means for attaching said frame members to the longitudinal frame of a motor vehicle, a frame secured to and supported on said frame members and extending transversely thereof, a snow board extending along the transverse frame, supporting rollers carried by said snow board and adapted to rest on the surface on which the motor vehicle is operated, sprocket wheels mounted on said transverse frame adjacent the ends thereof, endless chains mounted on said sprocket wheels, means for driving said chains, and cross slats secured to and adapted to travel with said chains.

4. In combination, a motor vehicle, a power shaft thereon, a snow removing attachment, means for securing said attachment to said vehicle, operative devices on said attachment, a snow board extending along the attachment, and driving connections between said power shaft and said operative devices, said connections including a friction clutch located in a passage through the snow board.

5. A snow removing device, comprising a frame, means for attaching the frame to the front of a motor vehicle, said frame being adapted to extend across the front of the vehicle, a pair of endless chains supported on said frame adjacent the front and rear thereof, cross slats carried by said chains, bracing links pivoted to each slat and to the chains, and means for driving said chains.

6. A snow removing device, comprising a frame, means for attaching the frame to the front of a motor vehicle, said frame being adapted to extend across the front of the vehicle in front of it, a pair of endless chains supported on said frame adjacent the front and rear thereof transverse to the length of the vehicle, cross slats carried by said chains extending longitudinally of the vehicle, extensions on the slats beyond the front of said frame, and means comprising sprocket wheels on horizontal axes for driving said chains.

In testimony whereof I have hereunto affixed my signature.

GEORGE A. GULLBERG.
